UNITED STATES PATENT OFFICE.

WALTER TAYLOR AND SAMUEL HINDLE, OF FALL RIVER, MASSACHUSETTS,
ASSIGNORS OF ONE-THIRD TO WILLIAM E. SYNAN, OF FALL RIVER, MASSA-
CHUSETTS.

THREAD-TENSION DEVICE.

Application filed March 16, 1922. Serial No. 544,231.

To all whom it may concern:

Be it known that we, WALTER TAYLOR and SAMUEL HINDLE, citizens of the United States, residing at Fall River, in the county 5 of Bristol and State of Massachusetts, have invented certain new and useful Improvements in Thread-Tension Devices; and we do declare the following to be a full, clear, and exact description of the invention, such 10 as will enable others skilled in the art to which it appertains to make and use the same.

This invention relates to an improved thread tension device which is designed to 15 be used in connection with thread spooling and winding devices such as are used in cotton and wool mills.

The principal object of the invention is to generally improve upon tension devices of 20 this class by providing one which is practical and embodies a plurality of independently operable thread tensioning elements which are associated with a friction surface over which the thread is designed to pass, 25 this surface being movable and such in construction that it permits one or more of the tension elements to be rendered inoperative so that the tension can be accurately regulated to act on fine or coarse thread and 30 yarn.

Other objects and advantages of the invention will be apparent during the course of the following description.

In the accompanying drawings forming a 35 part of this specification and in which like numerals are employed to designate like parts throughout the same:

Figure 1 is a side elevational view of a 40 thread tensioning device constructed in accordance with this invention.

Figures 2 and 3 are front and rear elevational views of the device respectively.

Figure 4 is an enlarged detail section taken on the line 4—4 of Fig. 1.

Figure 5 is a central vertical sectional view taken on the line 5—5 of Fig. 4, showing one of the tension balls rendered ineffective.

Figure 6 is a view like Fig. 5 showing all 50 of the balls bearing on the thread.

Referring to the drawings by numerals, 1 designates generally a suitably designed supporting bracket having clamping means 2 arranged at its lower end designed to en- 55 gage a supporting rod or the like. At this

same end, the bracket is formed with an integral tapered spindle 3 designed to accommodate the bobbin (not shown). The upper end of the bracket is directed laterally and curved as indicated at 4 and is provided at 60 its free end with a laterally disposed thread guide 5. Emphasis is not to be laid on the construction of the supporting bracket, because in practice, any suitable design may be used.

The invention resides, as before indicated, in the provision of novel thread tensioning means which is supported on the upper curved portion 4 of the bracket. Broadly speaking, the tension means comprises a 70 friction surface over which the thread is designed to pass, this surface being so designed that when in a certain position it permits the threads to be relieved of pressure. Associated with this peculiarly designed friction 75 surface are a plurality of tension elements which operate independent of each other and serve to press the thread against the friction surface. One or more of these elements may be rendered ineffective by moving the friction surface in a manner to prevent contact of the thread with the desired element or elements. Specifically described, the above ends are accomplished by employing a rotary member or drum 6 having a 80 grooved periphery 7 constituting the aforesaid friction surface, this surface being depressed or counter-grooved as indicated at 85

to serve an important purpose to be herein-after clearly set forth. While on the drum, 90 it may be well to point out that it is provided on one side with an inclined or laterally directed retaining flange 9 which likewise serves a purpose to be made evident by the following description. As above intimated, 95 a plurality of separate and independently operable friction elements in the form of steel balls 10 are employed for co-operation with the thread T which is designed to pass over the grooved periphery of the drum be- 100neath the balls. For said drum and purpose of maintaining the balls in operative relation with respect to the friction surface, we make use of an arcuate holder 11 having stops 12 between which the several balls are 105 confined. This holder may be equipped with an arm 13 by means of which it will be connected to the bracket in the manner shown. In actual practice however, the holder may be made an integral part of the 110

device as it is not intended for movement. To insure effectiveness of operation of this device, the holder may be equipped with a guide 14 against which the thread is drawn 5 on its way to the spooling device. It may be conveniently mentioned here that the aforesaid retaining flange 9 is adapted to be arranged opposite the open side of the ball-retainer to hold the balls in the latter.

10 In practice, the bracket is clamped on a suitable supporting rod and a bobbin filled with thread is placed on the spindle 3, and the thread is passed through the guide 5 and over the friction surface or grooved periphery 7 of the rotary member 6 beneath the ball tension elements 10 which exert sufficient pressure on the thread to maintain it under an equal and uniform tension. When the member 6 is in the position shown 20 in Fig. 6 all four of the balls bear upon the thread. However, by loosening the nuts on the bolt which serves as a mounting for this member 6 and moving the latter to a position so that the depression or counter-groove 8 is disposed upwardly, the balls are 25 prevented from contacting the thread. According to the position of the friction surface, one or more, or even all of the balls can be maintained in a position where they 30 will not exert any pressure on the thread. The balls are capable of vertical and independent movement to compensate for knots and varying thicknesses of the cord and yarn and for this reason, the latter is seldom broken.

From the foregoing description it will be seen that we have devised an extremely novel and advantageous thread tensioning device which is such as to permit the tension to be 40 varied to accommodate different thicknesses of threads. The adjustment is accurate and can be changed rapidly. Inasmuch as persons skilled in the art to which the invention relates will doubtless be able to obtain 45 a clear understanding of the same after reading the description in connection with the drawings, a more lengthy description will be omitted.

Since probably the best results may be 50 obtained with the construction and arrangement herein shown and described, this is taken as the preferred embodiment of the invention. However, we wish it understood that minor changes coming within the scope 55 of the invention as claimed may be resorted to if desired.

We claim:

1. A thread tension device including a friction surface formed with a depression, 60 and a plurality of tension elements arranged to press the thread against said surface, one or more of said elements being rendered in-

effective when the depression is positioned therebeneath.

2. A thread tension device including a 65 friction surface having a cut away portion therein, and a plurality of thread tension devices co-operative with said surface, one or more of said elements being rendered inoperative when the aforesaid portion of said 70 friction surface is moved into alignment therewith.

3. A thread tension device including a plurality of independently operable tension weights, and an adjustable body opposed to 75 said elements and having a recessed friction surface, whereby to permit one or more of said elements to be rendered inoperative when the recess in said surface is positioned beneath said weights.

4. A thread tensioning device comprising an adjustable body provided with a cam-shaped friction surface over which the thread is adapted to be drawn, and relatively stationary tension means adapted to 85 press the thread against said surface, the tension on the thread being varied when said body is adjusted with respect to said means.

5. The structure set forth in claim 4, 90 wherein said tension means comprises a substantially horizontal row of ball-weights which contact the thread, one or more of said balls being moved out of contact with the thread when said body is adjusted. 95

6. A thread tensioning device embodying a plurality of ball-weights to contact the thread and place it under tension, and an adjustable body having a friction surface against which the thread is pressed, said 100 surface embodying means movable toward and from the balls to render one or more of them ineffective.

7. A thread tensioning device embodying an adjustable pulley and having a grooved periphery over which the thread is drawn, an arcuate substantially box-like ball container supported adjacent the periphery of 105 said pulley, said container having its bottom and one side open, a plurality of balls arranged in said container and passing through the open bottom to press the thread against the periphery of the pulley, said balls being removable through said open side of the container, and a guard flange on the pulley opposite the open side of said container for maintaining the balls in operative position, said flange being moved when the pulley is rotated to permit removal of one or more of the balls. 110

In testimony whereof we have hereunto set our hands.

WALTER TAYLOR.
SAMUEL HINDLE.
